GARMENT HANGER

Bernard B. Levine and Robert Phillips, New York, N.Y.,
assignors to Bernard Plastics Molding Corp., Brooklyn,
N.Y., a corporation

Filed Feb. 8, 1963, Ser. No. 37,488

Term of patent 14 years

(Cl. D80—8)

FIG. 1

FIG. 2

FIG. 3

FIG. 4

FIG. 5

FIG. 1 is a front view of a garment hanger showing our new design;

FIG. 2 is a top view thereof;

FIG. 3 is an enlarged cross-sectional view taken on line 3—3 of FIG. 1;

FIG. 4 is an enlarged cross-sectional view taken on line 4—4 of FIG. 1;

FIG. 5 is an enlarged cross-sectional view taken on line 5—5 of FIG. 1.

We claim:

The ornamental design for a garment hanger, substantially as shown.
